US00D848399S

(12) **United States Design Patent** (10) **Patent No.:** **US D848,399 S**
(45) **Date of Patent:** **** May 14, 2019**

(54) **PLAYBACK DEVICE**

- (71) Applicant: **Sonos, Inc.**, Santa Barbara, CA (US)
- (72) Inventors: **Gregory B. Burlingame**, Woburn, MA (US); **Mieko Kusano**, Santa Barbara, CA (US); **Wai-Loong Lim**, San Francisco, CA (US); **Jonathon Reilly**, Cambridge, MA (US); **Adrian Sesto**, Encino, CA (US)
- (73) Assignee: **Sonos, Inc.**, Santa Barbara, CA (US)
- (**) Term: **15 Years**
- (21) Appl. No.: **29/542,931**
- (22) Filed: **Oct. 19, 2015**

Related U.S. Application Data

- (63) Continuation of application No. 29/510,404, filed on Nov. 26, 2014, now Pat. No. Des. 746,795, which is (Continued)
- (51) **LOC (11) Cl.** **14-03**
- (52) **U.S. Cl.** **USPC** **D14/221; D14/218**
- (58) **Field of Classification Search**
USPC ..... D14/167, 168, 170-172, 188, 194-196, D14/204, 207, 209.1, 210-217, 221, 222, (Continued)

OTHER PUBLICATIONS

United States Patent and Trademark Office "Notice of Allowance", issued in connection with U.S. Appl. No. 29/446,524, dated on Sep. 9, 2014, 48 pages.

(Continued)

Primary Examiner — Keli L Hill
(74) *Attorney, Agent, or Firm* — KPPB LLP

(57) **CLAIM**

The ornamental design for a playback device, as shown and described.

DESCRIPTION

FIG. 1 is an isometric view of a playback device. FIG. 2 is another isometric view of the playback device of FIG. 1. FIG. 3 is a side view of the playback device of FIG. 1. FIG. 4 is another side view of the playback device of FIG. 1. FIG. 5 is another side view of the playback device of FIG. 1. FIG. 6 is another side view of the playback device of FIG. 1. FIG. 7 is a top view of the playback device of FIG. 1; and, FIG. 8 is a bottom view of the playback device of FIG. 1. The broken lines immediately adjacent the shaded areas represent the bounds of the claimed design while all other broken lines are included for the purpose of illustrating portions of the playback device; the broken lines form no part of the claimed design.

1 Claim, 5 Drawing Sheets

Related U.S. Application Data

a continuation of application No. 29/446,524, filed on Feb. 25, 2013, now Pat. No. Des. 721,061.

(58) Field of Classification Search
